UNITED STATES PATENT OFFICE.

AUGUSTUS T. PERKINS, OF OAK PARK, ILLINOIS, ASSIGNOR TO WEBSTER MFG. COMPANY, OF CHICAGO, ILLINOIS, A CORPORATION OF OHIO.

CAR SHIFTER.

Application filed January 31, 1924. Serial No. 639,630.

To all whom it may concern:

Be it known that I, AUGUSTUS T. PERKINS, a citizen of the United States, and resident of Oak Park, Cook County, Illinois, have invented a certain new and useful Improvement in Car Shifters, of which the following is a specification.

This invention relates to apparatus for moving cars on tracks, and more particularly to apparatus of this kind for shifting freight cars, such as cars containing grain, on to an unloading apparatus, or for any other purpose.

The object of the invention, therefore, generally stated, is to provide a novel and improved apparatus, operated hydraulically or by other suitable power, to engage a car and shift it along the track, or for pushing several cars along at a time, in an easy and expeditious manner, so that the cars may be moved from one place to another, as in unloading cars filled with grain, or for any other purpose, and whereby the necessity of using a locomotive will be obviated.

It is also an object to provide certain details and features of construction and combinations tending to increase the general efficiency and the desirability of a car shifting apparatus of this particular character.

To these and other useful ends the invention consists in matters hereinafter set forth and claimed and shown in the accompanying drawings in which—

Figure 1 is a side elevation of a car shifting apparatus embodying the principles of the invention, showing one end portion thereof broken away for convenience of illustration.

Figure 2 is a similar view showing that portion of the apparatus omitted in Figure 1, the two figures together constituting a complete side elevation of the apparatus.

Figure 3 is an enlarged transverse section on line 3—3 in Figure 1.

Figure 4 is an enlarged side elevation of the traveling carriage which engages the cars to move them from one place to another.

Figure 5 is a detail section on line 5—5 in Figure 4.

Figure 6 is an enlarged side elevation of a portion of the said apparatus.

Figure 7 is a plan of the apparatus shown in Figure 6.

Figure 8 is an enlarged plan view of some 55 of the apparatus shown in Figure 2.

As thus illustrated, referring to Figures 1 and 2, the invention comprises a carriage 1 having wheels 2 that travel on the tracks 3 located in the space 4 suitably formed 60 below the level of the rails 5 upon which the cars travel. This carriage has its upper portion 6 connected by oblique portions 7 with the pivotal points 8 on the carriage 1, which latter is horizontal, these pivotal 65 points providing a longitudinal axis about which the portion 6 is free to swing sidewise, as indicated in dotted lines in Figure 3 of the drawings. For propelling the carriage 1 in a direction to cause the desired shifting 70 movement of the cars, a cable 9 is connected to the front end thereof, and is then trained around the sheaves 10 and 11 mounted on the body frame 13 of the apparatus, and also around the sheave 12 mounted on the traveling carriage 14, which latter has wheels 15 that travel on the tracks 16 provided for this purpose. The end of the rope or cable 75 or other flexible connection 9 is attached at 17 to a stationary portion of the body frame 80 13, whereby a movement of the carriage 14 away from the sheaves 10 and 11 will cause the bumper 6 to travel toward said sheaves, thereby to move the cars in the desired manner.

For the operation of the carriage 14 one end thereof is connected by a rod 18 with the piston 19 in the hydraulic cylinder 20, the latter being supplied with fluid pressure in any suitable or desired manner, thereby 90 to move the piston back and forth therein. The rod 18 has its middle portion provided with a carriage 21 having wheels 22 that travel on the tracks 16 previously mentioned, thus supporting the rod against 95 buckling when subjected to endwise compression by the piston.

For the movement of the carriage 1 and the bumper 6 in the opposite direction, another carriage 23 is provided and equipped with wheels 24 to travel on the tracks 16 previously mentioned. This carriage is connected by rods 25 with the carriage 14, so that the two carriages move in unison, the rods or connecting members 25 being supported by guide rollers 26 on the carriage 21 previously mentioned. These members 25 can be wire ropes, if such is desired, or

any other connection can be used. When the piston 19 moves toward the sheaves 10 and 11, the rod 18 communicates this movement to the carriage 14, and the latter exerts a pull on the member 25 which is communicated to the carriage 23, whereby the bumper 6 and the carriage 1 are returned to the position shown in full lines in Figure 2, after having been moved to the position shown in dotted lines in Figure 1 of the drawings. This, it will be seen, is accomplished through the medium of a cable 27 which has one end fastened to the carriage 1 and is then trained around the sheaves 28, 29 and 30, the sheave 28 being mounted on the carriage 23, while the sheaves 29 and 30 are mounted on the body frame of the apparatus, and the other end of this cable 27 is then attached to the body frame at 31, whereby movement of the carriage 23 toward the sheaves 10 and 11 will cause the carriage 1 to travel in the opposite direction. When the piston 19 moves away from the sheaves 10 and 11, the cable 9 then exerts a pull on the carriage 1 to draw the latter toward the sheaves 10 and 11, and the carriage 23 will be moved toward the sheave 29 until the carriage 1 arrives at the position indicated in dotted lines in Figure 1 of the drawings.

Thus, in use, the carriage 1 is placed in position with the bumper 6 against one end of one of the cars, as shown in Figure 2, and the piston 19 is then operated to draw the carriage 14 away from the sheaves 10 and 11, thus causing the carriage 1 and the bumper 6 to push the cars forward in the desired direction. When the last car is disposed of, as shown in Figure 1, and when the bumper 6 has traveled as far as it can, this bumper is then swung outward to the position shown in Figure 3, so that it may pass any cars which have been pushed on to the track in the meantime by a locomotive, or by other means. When the piston 19 is reversed the carriage 1 and the bumper 6 will then travel back to the position shown in full lines in Figure 2, and the bumper 6 can then be swung back into position to engage a car, and the operation will then be repeated. Of course, the apparatus can be used to move one car at a time, if it is not expedient or desirable to move several cars at the same time. In such case, the bumper 6 will engage the car nearest the unloading apparatus (not shown) and will move this car into position. Then the motion will be reversed and the bumper will move back along one side of the next car, until it is in position to be swung over into engagement with the end of this car. In this way the bumper can move back to starting point at one side of a car, or at one side of several cars, and the apparatus can be used to move one car at a time or several cars at the same time.

The bumper can engage one end of a car standing on a track, move the car along in the desired direction, and then disengage and move along and engage the other end of the car, if it be desired to then return the car in the opposite direction.

Thus the necessity for using a locomotive is obviated, so far as the work of moving the cars one at a time into unloading position is concerned, the only use for a locomotive being that which is necessary outside of the range of operation of the hydraulically operated apparatus shown and described. A line of cars can be delivered in position, by a locomotive, and then the locomotive can withdraw and do other work while the apparatus shown and described is being employed to move the cars one by one, or successively, into position for the unloading of the contents thereof. It will be seen, therefore, that the invention contemplates a car moving apparatus to be employed as an adjunct, or as something auxiliary to a car unloading apparatus, or of apparatus for even loading the cars, or for doing other work. In other words, the apparatus can be used for shifting the cars for any suitable or desired purpose, and contemplates the use of a bumper which will travel in a slot 32 formed at one side of the rails 5 previously mentioned, this slot being wide enough to permit the bumper to swing laterally to one side, so that it can return to starting point in the manner described. By referring to Figure 3 of the drawings, it will be seen that the slot 32 is immediately below the left hand rear and lower corner of the car, but it is obvious that the bumper may be used at either side of the rails 5, without departing from the spirit of the invention. The cylinder 20 is supported in any suitable manner, of course, in stationary position, and the operation of the piston 19 is controlled in any suitable or desired manner, thereby to ensure the mode of operation shown and described.

With the arrangement shown and described, which is illustrative of the invention, it will be seen that the entire apparatus is practically below ground, and below the plane of the rails 5 upon which the cars travel. The upper portion of the member 7 is exposed, and extends upwardly through the slot 32, and is free to travel along in this slot in the manner described. Moreover, the member 7 travels faster than the piston 19, inasmuch as the sheaves multiply the speed, whereby a comparatively short travel of the piston will result in a considerably greater travel on the part of the member 7 and the cars on the track. Thus, with a stationary power device having only relatively low speed, and a comparatively short range of motion, the cars are shifted at relatively high speed and with a much

greater range of motion, so that with a comparatively short stroke of the piston the cars will move quite a distance one way or the other on the track.

5. As shown in Fig. 5 the lower end of the member 7 can have a short downwardly extending arm 33, and the truck may have stops 34 and 35 at opposite sides of this arm, arranged in position to limit the lateral movement of the member 7, in an obvious manner.

Thus one and the same element 6 is adapted for pushing a car in either direction, and is adapted to engage either end of the car for this purpose. Therefore, of course, the element 6 is operative to engage one of the cars shown and push it to the right, or the apparatus may be moved along so that this element can engage the other end of this same car, and then push the car in the opposite direction. Thus the car pusher is reversible for the purpose of pushing cars in opposite directions on one and the same track, and pushing of a car, or of several cars, in either direction, is accomplished by a single element adapted to engage either end of a car.

What I claim as my invention is:—

1. In apparatus for shifting railway cars along a track, the combination of a traveling carriage movable parallel with the track, having a member adjustably mounted thereon for engaging and disengaging either end of the car, for pushing the car in either direction, and instrumentalities including a power device in stationary position and a cable system and sheaves cooperating to cause back and forth movement of said carriage at greater speed than the speed of said power device, whereby cars are movable successively along said track, some distance, in either direction, with relatively slight movement of said power device.

2. A structure as specified in claim 1, said power device comprising a fluid operated piston, said instrumentalities comprising cables attached to the opposite ends of said carriage, sheaves mounted on stationary portions of the apparatus to support said cables, and traveling carriages operated back and forth by said piston to cause said cables to move said member and its carriage in either direction.

3. A structure as specified in claim 1, said instrumentalities comprising a sheave carriage operated by said power device, another sheave carriage operated by said first mentioned sheave carriage, cables attached to the opposite ends of said engaging member carriage and trained around the sheaves of said sheave carriages, and sheaves mounted on stationary portions of said apparatus to support said cables, whereby movement of the two sheave carriages in one direction will move the engaging member car-

riage in the opposite direction, while movement of said sheave carriages in the opposite direction will move said engaging member carriage in said one direction.

4. A structure as specified in claim 1, said member being pivoted to tilt out of the path of the cars, whereby the member and its carriage may be returned to starting point along one side of one or more cars, the range of travel of said member being greater than the range of motion of said device.

5. A structure as specified in claim 1, said apparatus comprising means for enclosing said carriage and forming a slot for said member at one side of the track upon which the cars travel, along which slot said member is free to travel, so that except for said member the apparatus is enclosed, together with tracks below said slot to support said carriage, said slot being narrower than the carriage.

6. A structure as specified in claim 1, said power device comprising a cylinder having a hydraulically operated piston therein, and sheave carriages operated by said piston, together with cables operated by said sheave carriages, all forming a part of said instrumentalities.

7. In a car shifter, the combination of a carriage arranged to travel at one side of the track upon which the cars travel, an underground track for said carriage, whereby the carriage is operative in a plane below the plane of said track, an exposed member on said carriage to engage and move the cars in either direction on said track, apparatus below the underground track to operate said carriage, and means for permitting lateral movement of said member, whereby the carriage and its said above-ground member may travel along at one side of one or more cars.

8. A structure as specified in claim 7, in combination with means including cables and speed multiplying sheaves and a power device for moving said carriage in either direction of travel thereof.

9. A structure as specified in claim 7, in combination with a piston and cylinder and means operated thereby to move said carriage with said member thereon in either position thereof.

10. A structure as specified in claim 7, said means for permitting lateral movement of said member comprising pivots forming a longitudinal axis of movement for said member below ground on said carriage.

11. A structure as specified in claim 7, comprising means to enclose said carriage and to form a slot at one side of the car track, in which slot said member is adapted to travel, said slot being narrower than said carriage but of a width to permit said lateral movement of said member.

12. A railway car shifter comprising means movable in either direction at one side of the car track, parallel therewith, adapted to engage and propel a car or cars along the track, and to disengage a shifted car and travel back to get another car, the same element of said engaging means being operative to engage either end of a car standing on the track, thereby to push the car in either direction, and means operating at relatively slow speed by hydraulic pressure to operate said engaging means at relatively high speed.
13. In apparatus for shifting railway cars on a track, the combination of a traveling shifter carriage having a member thereon for engaging the car, a guide parallel with the track for said carriage, below the plane of the track, and instrumentalities including a power device in stationary position to cause back and forth movement of said carriage in the desired manner, said instrumentalities comprising a sheave carriage operated by said power device, another sheave carriage operated by and disposed in the plane of said first mentioned sheave carriage, in a plane below said shifter carriage, cables attached to the opposite ends of said engaging member carriage and trained around the sheaves of said sheave carriages, and sheaves mounted on stationary portions of said apparatus to support said cables, whereby movement of the two sheave carriages in one direction will move the engaging member carriage in the opposite direction, while movement of said sheave carriages in the opposite direction will move said engaging member carriage in said one direction.
14. In apparatus for shifting railway cars on a track, the combination of a traveling shifter carriage having a member thereon for engaging the car, a guide parallel with the track for said carriage, below the plane of the track, and instrumentalities including a power device in stationary position to cause back and forth movement of said carriage in the desired manner, said power device comprising a cylinder having a hydraulically operated piston therein, and sheave carriages in a plane below said shifter carriage, operated by said piston, together with cables operated by said sheave carriages, all forming a part of said instrumentalities.
15. In a car shifter, the combination of a carriage arranged to travel at one side of the track upon which the cars travel, a member on said carriage to engage the cars, and means for permitting lateral movement of said member, whereby the carriage and its said member may travel along at one side of one or more cars, in combination with a piston and cylinder and means operated thereby to move said carriage with said member thereon in either position thereof.
16. In apparatus for shifting cars, the combination of a traveling carriage having a member thereon for engaging the car, and instrumentalities including a power device in stationary position to cause back and forth movement of said carriage in the desired manner, said apparatus comprising means for enclosing said carriage and forming a slot for said member at one side of the track upon which the cars travel, along which slot said member is free to travel, so that except for said member the apparatus is enclosed, together with tracks below said slot to support said carriage, said slot being narrower than the carriage.
17. In a car shifter, the combination of a carriage arranged to travel at one side of the track upon which the cars travel, a member on said carriage to engage the cars, and means for permitting lateral movement of said member, whereby the carriage and its said member may travel along at one side of one or more cars, comprising means to enclose said carriage and to form a slot at one side of the car track, in which slot said member is adapted to travel, said slot being narrower than said carriage but of a width to permit lateral movement of said member.
18. In a car shifter, the combination of a carriage arranged to travel at one side of the track upon which the cars travel, an underground track for said carriage, an exposed member on said carriage to engage the cars, and means for permitting lateral movement of said member, whereby the carriage and its said above ground member may travel along at one side of one or more cars, comprising means to enclose said carriage and to form a slot at one side of the car track, in which slot said member is adapted to travel, said slot being narrower than said carriage but of a width to permit lateral movement of said member.

AUGUSTUS T. PERKINS.
